UNITED STATES PATENT OFFICE.

JAMES A. OBERMILLER AND PHILIP EICKENBERG, OF CHICAGO, ILLINOIS.

PANEL-BOARD SWITCH.

1,082,759.

Specification of Letters Patent. Patented Dec. 30, 1913.

Application filed July 29, 1912. Serial No. 712,187.

To all whom it may concern:

Be it known that we, JAMES A. OBERMILLER and PHILIP EICKENBERG, citizens of the United States, residing at Chicago, in the county of Cook and State of Illinois, have invented certain new and useful Improvements in Panel-Board Switches, of which the following is a specification.

Our invention relates to improvements in panel-board switches and has for its general object to improve the structure of such devices so that they may be quickly applied to the branch bars of a panel-board for support upon the board, that they may be of simple construction in their supporting and appurtenant parts, and that they may be well protected by cover members applicable thereto in advantageous fashion.

Other objects of our invention will become apparent to those skilled in the art from a consideration of the following drawing, wherein—

Figure 1 is a plan of a device constructed in accordance with our invention, with the cover in section; Fig. 2 is a sectional view on line 2—2 of Fig. 3; Fig. 3 is a sectional view on line 3—3 of Fig. 1, showing the cover in section and the switch device in elevation; and Fig. 4 is an enlarged detail of the connection between a supporting contact-member of the switch device and a branch bar of the panel-board.

In the drawings, 5 indicates a panel-board of insulating material upon which are mounted the usual branch bars arranged in pairs, each bar being broken so that there is formed by each pair of bars so broken, four confronting ends 6—7 and 6—7. It will be noted from the description hereafter given that our device is constructed with this particular environment in mind to make it better adaptable to such use.

The switch device shown is, of course, of the double-pole type, and since the details of these structures are common and well known in the art we will refer only to such parts thereof as enter into the embodiment of our invention.

8 indicates an insulating block upon which are supported a stationary contact, a movable contact, a means for operating said movable contact, and a cover for overlying all of said parts.

9 indicates in general a contact-operating means for operating the movable contacts 10—10, this structure including a metallic

supporting frame 11, and the usual push-buttons 12. As a convenient means of securing the frame 11 to the insulating block we provide a metallic plate 13 in a suitable recess in the upper surface of the block, and connect this plate with the frame 11 by means of screws 14, so that upon tightening of the screws the frame 11 of the contact-operating parts and the plate 13 are firmly supported upon the insulating block. As will hereafter appear, our invention contemplates the utilization of the plate 13 for purposes in addition to that of supporting the frame 11 upon the block.

Extending from opposite sides of the insulating block 8, we provide metallic legs 15—15 and 16—16, each bent downwardly from its point of connection with the block as at 17 to provide a long straight portion 18, and at 19 bent at right angles to form a flat portion 20 paralleling the block 8, said portion 20 having a lug 21 perforated for purposes to be described, and extending laterally beyond the block 8.

Secured upon each of the metallic leg-members, is provided an inwardly extending contact member 22, constituting the stationary contact with which the corresponding movable contact 10 is adapted to coact. It will thus be seen that the lugs 21 constitute the terminals of the switch device, having connection with the stationary contact of said switch device through the legs 15 and 16, such legs, as will hereafter more clearly appear, constituting the means by which the device is supported upon the branch bars of the panel-board.

Near each end of the metallic plate 13, we provide screw-threaded perforations 23. Overlying the insulating block 8 and extending down over the contact-operating parts and supporting legs we arrange a suitably constructed cover member 24, the edge of said cover member adapted for coaction with the panel-board 5, and the top of the cover member being suitably perforated as at 25, loosely to receive the push-buttons 12. The top of the cover is also provided with perforations registering with the perforations 23 in the plate 13 to receive screws 26, said screws engaging in the perforations 23 in plate 13.

We have stated that the lugs 21 of the leg members were perforated and extend laterally beyond the insulating block 8, so that the switch device may be supported

by means of said leg members upon the branch bars of the panel-board. To receive the leg members, the branch bars are bent upwardly as at 27, and each upwardly bent 5 end is provided with a screw-threaded perforation for a screw 28. In attaching the device to a panel-board having its branch bars so arranged, it will be apparent that the lugs 21 extend laterally beyond the 10 block and the block-carried parts, so that access may readily be had to the screws 28, and that when said screws are tightened the device is firmly secured at four points. When the insulating block and block-carried 5 parts have been thus secured by means of the leg members described, the cover member may be placed over the block with its perforations 25 receiving the push-buttons when the screws 26 may be placed in the 20 registering perforations in the cover and in the plate 13, and when said screws are tightened, the edge of the cover will be pressed into dust-proof contact with the panel-board 5, the cover being, of course, suitably 25 shaped to accommodate passage thereunder of the branch bars 6 and 7, as at 29.

Of course, the advantages to be gained by the use of a push-switch constructed in accordance with our invention will readily 30 appear to those skilled in the art, but among them we may mention that the device may be applied to the panel-board without alteration thereof except that the branch bars be severed as described and that in this way, 35 although the panel-board is left intact, the cover is so arranged that it makes dust-proof fit with the panel board. Further, the advantages of providing leg members which carry the stationary contacts as described will readily appear. These and other advantages attained by the specific embodiment herein shown, are also attainable by other embodiments of our teachings, and we do not therefore limit our invention to 40 the particular embodiment shown further than specified in the appended claims.

What we claim is:—

1. In a device of the character described, the combination of a panel-board having 50 branch-bars terminating in an area for supporting-attachment to the legs of a switch device, the panel-board being imperforate at said area, and a switch device comprising an insulating block, metallic leg members mounted on said block, means on said block electrically to connect or disconnect said legs, and means of connection between said legs and the branch-bars of the panel-board for support of said device by said 55 branch-bars through the agency of said electrically-connectible legs, whereby the panel-board may be left intact.

2. In a device of the character described, for use with the branch-bars of a solid 60 imperforate panel-board, the combination of

a cover member adapted to overlie a contact-operating means; mechanism within said cover, connected to the cover and including contact-operating means operable from without the cover, metallic supporting 70 legs, movable contacts carried by said contact-operating means, stationary contacts carried by said legs, the legs having their lower ends formed for coaction with an attaching means; and means for attaching said legs to the branch-bars of the panel-board; said cover having its free edges formed for coaction over the branch-bars and into contact with the upper surface of said imperforate panel-board. 80

3. In a device of the character described, the combination with the branch-bars of a panel-board, of an insulating block, contact-operating means mounted thereon, metallic leg members adapted to be electrically connected or disconnected by said contact-operating means, said legs extending from the block around the contact-operating means, and means to connect said legs to the branch-bars of the panel-board, said legs and branch-bars being suitably bent to receive 90 said connecting means independently of the panel-board. 95

4. In a device of the character described, the combination of an insulating block, metallic legs extending from opposite edges of said block and bent downwardly in substantial parallelism and thence bent inwardly at right angles to inclose a contact-operating means, each said leg member having mounted thereon an electric contact, contact-operating means mounted upon said block for electrically connecting and disconnecting the leg-carried contacts, and means for supporting said block and block-carried 100 parts by said legs. 105

5. In a switch device of the character described, the combination with the branch-bars of a panel-board, each of said branch-bars having screw-receiving perforations and screw-clearances thereunder, of a switch device provided with downwardly bent metallic legs, each leg being bent inwardly at its extremity and having a screw-receiving perforation registering with the screw-receiving perforation in the respective branch-bars, and a screw for each said leg taking through said registering perforations, whereby said switch device is supported upon the panel-board by engagement 110 between the legs thereof and said branch-bars, as described. 115

6. A device of the character described, comprising, in combination with the branch-bars of a panel-board, each of said branch-bars having screw-receiving perforations and screw-clearances thereunder, a switch device provided with downwardly bent legs, each leg being bent inwardly at its extremity and having a screw-receiving perforation in 120 125 130

a lug provided by said inwardly bent portion of the leg, said perforated lug extending laterally beyond the switch device, and screws taking through said inwardly bent portions of the legs and engaging in said screw perforations in the branch-bars of a panel-board.

7. In a device of the character described, for use with the branch-bars of a solid ¹⁰ 10 perforate panel-board extending in pairs toward each other, comprising leg members each secured at its lower end to the end of one of said branch-bars independently of the

panel-board, an insulating block secured to the upper ends of said four leg members, ¹⁵ and means carried by said insulating block electrically to connect and disconnect said legs in pairs for electrical connection of the corresponding pairs of branch-bars.

In testimony whereof we hereunto set our hands.

JAMES A. OBERMILLER.
PHILIP EICKENBERG.
